UNITED STATES PATENT OFFICE.

HANS BRINCK, OF LOS ANGELES, CALIFORNIA, ASSIGNOR OF FORTY-NINE ONE-HUNDREDTHS TO LOUIS E. BERGERON, OF CHICAGO, ILLINOIS.

CUTTING DEVICE FOR OPENING PLASTER CASTS ON THE BODIES OF INJURED.

1,269,373.

Specification of Letters Patent. Patented June 11, 1918.

Application filed August 21, 1917. Serial No. 187,456.

To all whom it may concern:

Be it known that I, HANS BRINCK, a subject of the Emperor of Germany, residing at Los Angeles, in the county of Los Angeles and State of California, have invented a new and useful Cutting Device for Opening Plaster Casts on the Bodies of Injured, of which the following is a specification.

This invention relates to a cutting device 10 and particularly pertains to a device for opening plaster casts.

It is the principal object of this invention to provide a cutting device which may be mechanically operated to cut through the 15 walls of a plaster cast while it is in position upon the body and which will operate to form a straight cut the length of the cast and entirely therethrough without danger of injuring the skin therebeneath or causing 20 pain during the operation.

Another object of this invention is to provide a device to produce the above results which will open the plaster cast and allow it to be preserved so that it may be replaced 25 around the injured member and thus reused.

Other objects will appear hereinafter.

The invention is illustrated, by way of example, in the accompanying drawings in 30 which:

Figure 1 is a view in plan illustrating the cutting device with parts broken away and particularly disclosing the manner in which the cutter is mounted and driven.

Fig. 2 is a view in side elevation illustrating the assembled cutter with a portion of the handle broken away and disclosing in detail the protecting plate, the spacing member, and the cutter mounting.

Fig. 3 is a fragmentary view illustrating in a diagrammatical manner the operation of the cutting tool and the position of a cast clamp around the cast.

Fig. 4 is a view in transverse section on the line 4—4 of Fig. 2 disclosing the formation of the protecting plate.

Fig. 5 is a view in end elevation illustrating one of the cast clamps.

Fig. 6 is a view in side elevation illustrating the bolt used with the cast clamp.

Referring more particularly to the drawings, 7 indicates a handle having a grip portion at one end and a rectangular handle fork at its opposite end. Interposed between the side arms of the fork is a pair of

driving gears 9, one of which is mounted upon a spindle 9', while the other is mounted upon a spindle 10'. This spindle is provided with a circular cutting member 10, the periphery of which is formed with cutting teeth. Formed at the end of the fork 8 and extending outwardly therefrom is an extension lug 11. Hinge plates 12 are secured by a pivot pin 11' at opposite sides of said extension lug, and are connected at their opposite ends to an upwardly extending lug 13 by a pin 13'. This last-named lug is formed integral with a combined guide and shield plate 14 adapted to pass between the body of the patient and the cast to protect 70 the skin from the cutting member and to form a stop face for a distance pin 17 which will strike the plate when the cutting member has passed entirely through the wall of the cast. A longitudinally extending groove 75 16 is formed along the upper face of the shield and insures that the cutting member will entirely pass through the wall of the cast in a manner which will be readily understood.

In operation, the cutting device is used as shown in its assembled position in Fig. 2. At this time the forward edge of the shield plate 14 is slipped between the cast and the injured member. As this is drawn into 85 position an operating crank 15 is actuated to rotate the spindle 9' and in turn impart motion to the gears 9 and the cutter spindle 10'. When this handle is rotated in the direction of the arrow —a—, cutter 10 90 will be rotated in the direction of the arrow —b—, as indicated in Fig. 2. The shield is held motionless while the handle 7 is swung downwardly in the direction of the arrow —c— in Fig. 2 until the periphery of the cutter has entirely passed through the wall of the cast. This will be indicated by the distance pin 17 which will be brought to bear against the upper face of the shield member 14. The rotation of the crank may then be 100 continued as the entire device is drawn along the cast, as shown in Fig. 3. During the cutting operation, circular clamping members 21 may be placed around the cast 20 to prevent its breaking, as shown in Fig. 3. 105 These clamping members are formed with split ends 22 adapted to receive a clamping bolt 23 as particularly shown in Fig. 6. It will thus be seen that the device here disclosed is simple in its construction, may 110

be easily applied, and operated without pain to the patient or inconvenience to the operator, and will act upon the cast in a manner to permit it to be re-used if desired,

5 While I have shown the preferred construction of my cutting device for opening plaster casts as now known to me, it will be understood that various changes in the combination, construction and arrangements 10 of parts may be made by those skilled in the are without departing from the spirit of my invention as claimed.

I claim:

1. A cutting device for opening plaster 15 casts, comprising a shield plate adapted to be interposed between the wall of a cast and an injured member inclosed thereby, a fixed lug extending upwardly from one end of said plate, a handle pivotally mounted to 20 said lug for radial and longitudinal movement in relation to the plate, a rotary cutting member mounted upon the handle and adapted to swing therewith, driving gears by which the cutting member is driven, a crank rotating said driving gears, and a stop pin

extending downwardly from the handle to strike the plate when the periphery of the cutting member has passed through the wall of the plaster cast.

2. A cutting device for opening plaster 30 casts, comprising a shield plate having a longitudinally extending groove in its upper face, a lug extending upwardly from one end of the shield plate, hinged plates pivotally connected to the lug, an extension lug pivotally connected to the hinged plates, a fork rigid with the extension lug, a handle rigid with the fork, a pair of driving gears operatively mounted in the fork, a crank for operating one gear, a circular cutting member 40 mounted upon the spindle of the other gear in line with the groove in the shield, and stop means to limit the downward swing of the fork.

In testimony whereof I hereunto affix my signature in the presence of two witnesses.

HANS BRINCK.
